UNITED STATES PATENT OFFICE.

PHILIP K. WILLIAMS, OF GLASTONBURY, CONNECTICUT, ASSIGNOR TO J. B. WILLIAMS COMPANY, OF GLASTONBURY, CONNECTICUT, A CORPORATION OF CONNECTICUT.

COMBINED SHAVING-STICK HOLDER AND CASE.

1,006,420.

Specification of Letters Patent. Patented Oct. 17, 1911.

Application filed December 27, 1910. Serial No. 599,585.

To all whom it may concern:

Be it known that I, PHILIP K. WILLIAMS, a citizen of the United States, residing at Glastonbury, Hartford county, State of Connecticut, have invented certain new and useful Improvements in Combined Shaving-Stick Holders and Cases, of which the following is a full, clear, and exact description.

My invention relates to a combined shaving stick holder and case, and embodies many features of advantage, as hereinafter described.

In the drawings, Figure 1 is a side elevation of the case complete, the soap stick and holder being assembled therewith. Fig. 2 is a side elevation of the stick and holder detached from the case. Fig. 3 is a longitudinal section of the parts shown in Fig. 1. Fig. 4 is a section on the line $x-x$ of Fig. 3. Fig. 5 is a plan view of the holder alone. Fig. 6 is a side elevation thereof. Fig. 7 is a plan view of a detached detail. Fig. 8 is a side view of the same detail. Fig. 9 is a section of the soap stick alone on the plane of the line $x-x$ of Fig. 3, looking down. Fig. 10 is a side elevation of the lower end of the soap stick.

1 is an external metallic shell constituting the main body of the case, the same being closed at one end.

2 is a lining of heavy paper, or the like, which extends out to the edge of the case at the open end for the purposes hereinafter described.

3 is a stick of soap.

4 is an annular groove in the side of, and near one end of, the stick 3.

5-5 are longitudinal grooves leading from the end of the stick to the annular groove 4, the function of which will later be seen.

The holder, in its preferred form, comprises a cup-shaped shell 6, having a contracted portion 7 to form a holding shoulder, said contracted portion being of an internal diameter corresponding closely to the external diameter of the stick 3. Within the shell 6 is a lining piece 8 held therein in any suitable way, the said lining piece constituting a step for the lower end of the stick 3 below the groove 4. If desired, the shell 6 may have an extension 9.

10 is an incline between the contracted portion 7 and the main body of the shell 6.

55 The main body of the shell 6 is so propor-

tioned as to snugly fit into the open end of the lining 2 of the case 1.

11 is a vent piercing the wall of the case 1 and the lining 2.

12 is a mass of solidified plastic material arranged within the shell 6, said material completely filling the space therein and projecting into the annular groove 4, so as to lock the stick 3 in the shell 6. When the stick is inserted into the shell 6, the plastic material should be in liquid state so that as said stick is forced in, said material will flow through the passages 5 into, and completely around, the annular groove 4, thereby effectively anchoring said stick within said shell. One or more of these grooves 5 is important because any plastic material in the bottom of the step 8 could not otherwise escape therefrom as the stick is being forced in. Since the step 8 furnishes a very substantial support for the lower end of the stick 3, it follows that said groove or grooves 5 perform a very important function in permitting the proper assembling of the parts. The plastic material is preferably of some waterproof compound which will, on cooling, harden, paraffin being one suitable material for this purpose. By reason of the waterproof character of the stick anchoring material, that part of the stick within the shell is effectively protected from moisture, and hence the soap at that point cannot become dissolved so as to weaken the connection between said cap and shell. The lining 2 performs two important functions; first, by extending out to the edge of the open end of the case 1 it prevents direct contact of the side of the soap with the relatively sharp metal edge upon inserting the stick, thereby preventing the gouging of the side of the stick; second, being relatively yielding as compared with metal, it enables the shell 6 to be forced into friction tight contact so as to securely hold the stick snugly housed within the case 1.

100 The function of the vent 11 is to permit the escape of air from the case 1 when the shell 6 is being pushed home. The snugness of the fit of the shell 6 within the lining 2 is such that air cannot escape around the shell, and if, after a time, the lining near the open end of the case 1 should become lubricated by the soap, it is obvious that a pressure of air within the case would tend to force out the shell 6 and stick 3. To 105 110

avoid this, the vent 11 is, by preference, provided, said vent being preferably so placed that when the shell 6 is fully seated, it will just cover said vent, and thereby effectively seal, from the air and moisture, the interior of the case 1.

What I claim is:

In a combined shaving stick holder and case, a metallic case element open at one end only, a combined metallic holder and stopper, a lining of relatively yielding ma-

terial within the case extending to and protecting the edge at the open end thereof, said holder and stopper element being adapted to snugly fit within the outer end of the lining, and a soap stick carried by said combined holder and stopper. 15

PHILIP K. WILLIAMS.
